UNITED STATES PATENT OFFICE.

GEORGE S. MURPHY, OF DES MOINES, IOWA, ASSIGNOR TO THE ARMAND COMPANY,
OF DES MOINES, IOWA.

HOLDING AND SHIPPING INSERT.

Application filed September 13, 1926. Serial No. 135,100.

The object of my invention is to provide a holding and shipping insert particularly adapted for holding a pair of flat containers and a tube container in proper position.

5 More particularly my invention relates to an insert made of a single piece of paper adapted to have openings therein for permitting containers to be secured therein and adapted to have portions folded upon themselves whereby the containers may be held fastened to the shipping insert whereby the entire assembly may be placed in an envelope for mailing purposes.

10 Still a further object is to provide a shipping insert adapted to have a pair of flat containers secured thereto and a tubular container mounted between the two flat containers and covered in such a manner as will prevent the containers from movement relative to each other and from pulling loose from the shipping insert, the cover section of the shipping insert being made of two sections and bendable upon an inclined line 25 so that the side edges of the assembled shipping insert will be comparatively flat thus forming a real protective edge for the entire assembly.

With these and other objects in view, my invention consists in the construction, arrangement and combination of the various parts of my invention, whereby the objects contemplated are attained, as hereinafter more fully set forth, pointed out in my 35 claims, and illustrated in the accompanying drawings, in which:

Figure 1, is a plan view of the blank forming my holding and shipping insert.

Figure 2, is a plan view of the shipping insert folded in position with parts broken away for better illustrating the construction and showing a tube and flat container secured to the holder.

Figure 3, is a sectional view taken on line 40 3—3 of Figure 2.

Figure 4, is a sectional view taken on line 45 4—4 of Figure 2.

Figure 5 is a sectional view taken on line 50 5—5 of Figure 2, and.

Figure 6, is an end view illustrating how the cover is bowed when the parts are completely assembled.

In the accompanying drawings I have used the reference character A to indicate

generally a rectangular sheet of paper 55 formed with a bottom portion 10 having a pair of openings 12 therein.

The material adjacent the openings 12 is formed with a number of slits 14 whereby a flat container 16 may be inserted through 60 one of the openings 12. The slits 14 permit the container 16 to be forced through the opening 12 and yieldingly held therein thereafter.

The containers 16 are adapted to contain 65 cold cream or other cosmetics and are simply held upon the bottom portion 10. The bottom portion 10 is defined between two scored lines 18 and 20.

The entire sheet illustrated in Figure 1 above the dotted or scored lines 18, is adapted to be folded upon the scored line 18. Within the portion above the scored line 18 and substantially equi-distant from the 70 openings 12, is a small opening 22 adapted to receive the head 24 of a cosmetic tube 26.

The tube 26 is clearly illustrated in Figure 5 of the drawings and when the head 24 is received within the opening 22, it will lie 75 flat between the two openings 12 or the containers 16 when they are in the openings 12.

A triangular shaped portion 28 is defined by the scored line 18 and the scored lines 30. The portion of the sheet A above the lines 80 30 forms cover sections 32. The cover sections 32 are separate from each other.

The blank A is cut-away as at 34 which causes the cover sections 32 to be spaced apart. The adjacent edges of the cover sections 32 are inclined outwardly and away 85 from each other so that the space between the cover sections near the upper end as illustrated in Figure 1 of the drawings, is further apart than at the lower ends.

The upper edge of each of the sections 32 is inclined upwardly and towards the center or cut-away portion 34. The cover sections 32 are adapted to be bent upon the scored lines 30 and when the cover sections 90 32 are so bent, the adjacent edges thereof will practically abut against each other.

The arrangement of the inclined scored lines 30 enables the cover sections to rest 95 substantially against each other when they are bent over and serve as cover sections.

The inclined edges formed by the cut-away portion 34 are substantially vertical

when the cover sections are in the position as illustrated in Figure 2 of the drawings. The portion 36 may be considered a flap and adapted to be folded over the free ends 5 of the cover sections 32.

The normal outer edge of the cover sections 32 are vertical and when they are bent over as illustrated in Figure 2, then the normal vertical edge becomes the inclined edge.

10 The portion of the blank A below the line 20 is referred to by the reference numeral 36 and this portion is bent up and covers the bottom end of the cover sections 32 after the containers 16 and 26 have been inserted 15 and mounted upon the shipping insert or blank A.

10 The outer or side edges of the cover sections 32 are adapted to rest substantially flush against the bottom 10 while the center 20 portion thereof is slightly bowed outwardly or spaced apart as clearly illustrated in Figures 3 and 6.

15 The portion 28 when bent upon the line 18 is inclined as clearly illustrated in Figures 4 and 5 of the drawings and serves to hold the tube 26 in position.

20 There is quite an advantage in having the outer edges of the shipping insert substantially against each other. The insert sheet 30 is adapted to be placed in an envelope and the narrow or flush edges of the shipping insert will provide a package which is neat and which is not bulky at the ends.

25 The portion 36 holds the cover sections 32 in proper position and tends to give to the package the narrow ends and bowed center as clearly illustrated in Figure 6 of the drawings.

30 My insert has proven very practical in connection with sampling of cosmetics where 40 two different kinds of cosmetics may be placed in flat containers and a third cosmetic placed in the tube. The tube 26 is arranged to be placed in position between the 45 two containers 16 and it of course, is wider than the containers and tends to help form a package which is very narrow at its side edges and larger at its center.

35 The sheet A is preferably formed of a 50 semi-stiff cardboard and after the containers are assembled thereon then it may be placed in an envelope with other mailing data and sent through the mails without any danger of the envelope becoming torn or demolished 55 due to the containers 16 and 26 which are metal.

40 Some changes may be made in the arrangement and construction of the various 60 parts of my device, without departing from the essential features and purposes of my invention, and it is my intention to cover by my claims any modified forms of structure or use of mechanical equivalents, which 65 may be reasonably included within their scope.

I claim as my invention:

1. A holder and shipping insert comprising a substantially rectangular sheet forming a bottom section, having at one edge a flap connected with it by a weakened line 70 and having one edge of a triangular top member connected therewith at its opposite edge, a pair of cover sections connected with the other edges of the top member along weakened lines, said cover sections having 75 diverging adjacent edges.

2. A holder and shipping insert comprising a substantially rectangular sheet forming a bottom section, having at one edge a flap connected with it by a weakened line 80 and having one edge of a triangular top member connected therewith at its opposite edge, a pair of cover sections connected with the other edges of the top member along weakened lines, said cover sections having 85 diverging adjacent edges, the width of the cover sections being such that when they are folded over against the bottom section and the flap is folded over, then the top member is held in position inclined at an acute angle 90 to the bottom member.

3. A holder and shipping insert comprising a flat bottom member, a triangular top member having one side connected with one edge of said bottom member along a weakened line, said top member being inclined away from the bottom member at an acute angle, a pair of cover sections connected with the other sides of the top member along 95 weakened lines and inclined from the top member toward the opposite edge of the bottom member and a flap connected along weakened lines with the bottom member at the edge thereof opposite the top member and overlying said cover sections.

4. A holder and shipping insert comprising a flat bottom member, a triangular top member having one side connected with one edge of said bottom member along a weakened line, said top member being inclined away from the bottom member at an acute angle, a pair of cover sections connected with the other sides of the top member along 100 weakened lines and inclined from the top member toward the opposite edge of the bottom member and a flap connected along weakened lines with the bottom member at the edge thereof opposite the top member and overlying said cover sections, said top member having a central opening.

5. A holder and shipping insert comprising a flat bottom member, a triangular top member having one side connected with one edge of said bottom member along a weakened line, said top member being inclined away from the bottom member at an acute angle, a pair of cover sections connected with the other sides of the top member along 105 weakened lines and inclined from the top member toward the opposite edge of the bottom member and a flap connected along weakened lines with the bottom member at the edge thereof opposite the top member and overlying said cover sections, said top member having a central opening.

bottom member and a flap connected along weakened lines with the bottom member at the edge thereof opposite the top member and overlying said cover sections, said top member having a central opening, said bottom member being provided with openings spaced on the opposite sides of said first opening.

6. A holder and shipping insert comprising a substantially flat bottom member, a triangular top member inclined at an acute angle from the bottom member, cover sections inclined from two sides of the top member toward the ends and opposite edge respectively of the bottom member, said

parts being connected together along weakened lines.

7. A holder and shipping insert comprising a substantially flat bottom member, a triangular top member inclined at an acute angle from the bottom member, cover sections inclined from two sides of the top member toward the ends and opposite edge respectively of the bottom member, said parts being connected together along weakened lines and a flap on said bottom member overlying the edges of said cover sections opposite the top.

GEORGE S. MURPHY.
